UNITED STATES PATENT OFFICE.

JOHN F. CAVANAGH, OF MERIDEN, CONNECTICUT, ASSIGNOR TO CONNECTICUT
TELEPHONE & ELECTRIC CO., OF MERIDEN, CONNECTICUT, A CORPORATION OF
CONNECTICUT.

SWITCH.

1,289,654.

Specification of Letters Patent. Patented Dec. 31, 1918.

Application filed August 9, 1917. Serial No. 185,236.

To all whom it may concern:

Be it known that I, JOHN F. CAVANAGH, a citizen of the United States of America, residing at Meriden, Connecticut, have invented a new and useful Switch, of which the following is a specification.

This invention relates to control switches for automobiles and is in the nature, as to some of its features, of a division from my 10 prior applications #123,785 and 184,321.

A special object of the present invention is to provide a compact, simple and inexpensive form of switch, particularly adapted for controlling the circuits of an automobile and which can be locked in position to prevent theft or tampering with the machine.

Another and more specific object is to provide a switch for controlling the lighting 20 mechanism and signaling circuits of an automobile which can be readily operated to control such circuits and which after being operated to put the circuits in a predetermined condition, may be locked with the 25 circuits in such condition.

Briefly the invention resides in the combination with a switch operating member for controlling one or more sets of switch contacts and a second independently operable switch controlling element of a unitary locking means for locking both of said switch controlling devices in desired relation. In the present embodiment of my invention the first switch controlling member 35 is in the form of a combined rotary and reciprocating push button for controlling by its rotary and push button movement two different sets of contacts and the second controlling member is in the form of a reciprocating switch closing button and the two controlling devices are locked by means of a single key plug having locking means operably engaging both of the aforesaid devices.

In the accompanying drawings, I have 45 illustrated the invention embodied in a practical and preferred form, but I would have it understood that changes and modifications may be made without departure from the true spirit and scope of the invention.

In said drawings,

Figure 1 is a side view of the invention as applied to the steering column of an automobile.

Fig. 2 is an edge view of the switch looking in the direction of the arrow 2 in Fig. 1.

Fig. 3 is a bottom plan view of the body or base portion of the switch.

Fig. 4 is a top plan view of the switch base and parts carried thereby.

Fig. 5 is a sectional view taken of the 60 switch substantially on the plane of the line 5—5 of Fig. 3.

Fig. 6 is a similar view taken substantially on the plane of the line 6—6 of Fig. 3.

Fig. 7 is an inside view of the combined 65 cap and operating push button.

Fig. 7^a is a broken sectional view taken substantially on the line 7^a—7^a of Fig. 7.

Fig. 8 is a cross sectional view of the locking cylinder taken substantially on the 70 plane of the line 8—8 of Fig. 3.

Fig. 9 is a diagrammatic view of the wiring and circuit arrangement for this type of switch.

Referring to the drawings more in detail, 75 10 designates the base of the switch usually formed of suitable insulating material and 11 designates the so-called push button or combined rotary and reciprocatory switch controlling member. Attached to the back 80 of the insulating base is a shell or casing member 12, which with the insulating base forms a housing for the switch terminals, said casing being shown provided with a conduit extension 13 through which the 85 circuit wires are led to the several terminals.

The push button is rotatably confined to the base in the present disclosure by providing it with a stem 14 working in a bore 15 in the base, the lower end of such stem extending through the under side of the base and having a screw 16 engaged therewith to limit the upward movement of the button. A spring 17 coiled about the stem yieldingly supports the button in an upright position 95 as shown in Fig. 6.

The push button carries at its under side a more or less centrally disposed push button contact 18 for engagement, upon depression of the button, with a co-operating contact 19 on the base and also carries two separated segmental contacts 20 and 21 for engagement with upstanding contacts on the base. These upstanding contacts extend from the under side of the base up through 100 passages extending through from the back to the front of the base and are sprung outwardly as most clearly indicated in Fig. 6, so as to engage with the contacts 20 and 21 which are seated in the dependent rim por- 105

tion 22 of the push button, said contacts being numbered 23, 24, 25, 26 and 27. (See Fig. 4.) At the under side of the base these contacts are shown provided with contact lugs 28, held in place by screws 29. The terminal of contact 24 is connected with the push button as by means of a strap 30 (Figs. 3 and 6.)

In use, the parts thus far described are connected in circuit as indicated in Fig. 9. The contact 27 being grounded by means of a suitable wire connection 28, the contact 26 being connected by wiring 29 with one of the head lights 30, the contact 25 being wired at 15 34 to the tail light 35, the contact 24 being connected by wiring 31 with a battery or other source of current 32 and the contact 23 by wiring 33 to a point in the connection between the head lights, the other one of the 20 head lights, the other side of the battery and the other side of the tail light all being grounded as indicated. In the position with the lights "off" the push button is rotated to the right so as to carry the short button contact 20 out of engagement with the base contacts and leaving the longer button contact 21 in engagement only with the base contacts 25, 26, 27, this position of the button contacts being indicated by the full lines in this 30 diagram. In this position no battery current reaches the button contacts and so far as the lights are concerned the switch is therefore "dead." If dim lights are required the push button is rotated one stop to the left so as to bring the two contacts on the button into the position indicated in dotted lines. The flow can now be traced from the battery through wire 31 to base contact 24 across button contact 21 to base contact 25, to the tail 40 light and ground and further along contact 21 to base contact 26 and by way of the wire 29 to the head lights in series and ground. This series connection of the head lights gives a dim light as well known. To secure 45 the full lighting effect, the button is turned a further step to the left bringing the button contacts into the position indicated in dot-and-dash lines in Fig. 9. In this condition the circuit to the tail light is the same as 50 above, but as the button contact 21 now touches the base contact 23, a path is opened up through connection 33 to a point intermediate the head lights where the current may divide and flow part through the left 55 head light and by way of wire 29, base contact 26, button contact 20, base contact 26, button contact 20, base contact 27 and connection 28 to ground and part through the right hand head light to ground. This, it 60 will be seen, is a parallel connection with the lamps receiving the full current force.

When the push button is depressed and the contact 18 on the under side thereof brought into engagement with the contact 65 19 on the base, a flow of current is provided

from the button contact 18, which is charged through connection 30 from the terminal of base contact 24, to the contact 19 which latter contact is connected by means of a wire 36 with a terminal 37 on the under side of the base which latter terminal is connected by wiring 38 with the horn or other signaling device 39 which latter device is grounded as indicated. It thus follows that upon depression of the push button, irrespective of 75 what position rotatably it may occupy, the circuit will be completed through the signaling device.

For the purpose of providing a good sliding contact between the upright contacts 23, 24, etc., on the base and the dependent contact segments on the button, the upstanding contacts may be rounded out as indicated in Fig. 4 and the dependent contacts 20 and 21 be hollowed as indicated in Fig. 7. These co-operating contacts serve to yieldingly retain the button in the positions to which it is rotated and additional notches 40 may be provided in the non-metallic portion of the dependent rim 22 into which the upstanding contacts fit with the button in the "off" position.

The locking means for the push button comprises in the particular embodiment illustrated a rotatable locking cylinder or plug 41 adapted to receive a suitable key 42, said plug being journaled at the under side of the insulating base at right angles to the axis of the push button and carrying at its inner end a radially extending arm 43 formed with a cam slot 44 receiving a pin 45 on the lower end of the locking pin or slide 46 which works up through the top of the base in position to engage in sockets 47, formed in the under side of the button. The locking cylinder 105 is held in the position to which it is turned by the key, by a detent 48 projected by a spring 49 into engagement with sockets or keeper surfaces 50, provided for it in the base.

The operation of this locking device will 110 be apparent from Figs. 3, 5 and 6 in the latter of which, it will be seen that as the point of the key is inserted in the plug, it will engage the forward end of the detent spring 49 and retract the detent from engagement with the socket 50 in which it has been seated. The plug can then be freely turned by the key. Thus, if the switch is in the unlocked condition, as indicated in Fig. 6 and the plug is rotated to the position indicated in Fig. 5, 115 the cam arm will project the locking pin up into engagement in one of the sockets 47, thus locking the push button in the position to which it has been turned and preventing further rotary manipulation of the push button. These sockets 47 in the push button may be made of such a depth that the locking pin when projected will extend to the bottom of the socket and thus lock the button against depression as well as rotation. 120 125 130

In the illustration (Figs. 7 and 7^a) two of these sockets are made relatively shallow so as to lock the button against push button movements and a third socket is made deeper 5 so as to permit the button when locked rotary in this last position to be depressed for the purpose of sounding the horn. This construction therefore enables the push button being locked either against both rotary 10 and push button movements or being locked against rotary movement alone.

In addition to controlling the lights and signaling mechanism my improved switch is adapted for the control of an additional 15 circuit, such as the ignition. The controller for this additional circuit comprises in the present disclosure a reciprocatory push and pull switch element 51 having a contact portion 52 adapted, when said control device is 20 pressed inward, to connect a pair of contacts 53—54. When the switch operating member 51 is drawn outward in the position indicated in Fig. 5 the contact portion 52 is freed from the contacts 53—54 and the circuit 25 thereby broken. The switch member may be locked in this position by means of an eccentrically disposed locking lug 55 on the inner end of the locking cylinder which, when the cylinder is turned into the position 30 shown in Fig. 5, is placed in front of the inner end of the member 51, thus locking it in its outer circuit broken position.

It will be clear therefore that by withdrawing the ignition plug and turning the 35 locking cylinder by means of the key to the position indicated in Fig. 5 both the ignition and the light circuits will be locked and, if the push button has been turned to bring one of the shallower locking sockets 47 into 40 the plane of the locking pin 46, the signaling circuit as well will be locked "off".

The switch may conveniently be mounted on the steering base or column 56 of a machine as shown in Fig. 1, it being for this 45 purpose provided with a yoke or clamp 57 adapted to embrace the steering column and secured to the back of the switch casing as by screws 58. Means for securing the switch casing together is preferably located beneath this supporting yoke so that when the switch is mounted in place, it will be impossible to get at the terminals without entirely 50 dismounting the switch. This securing means is hereby shown as a screw 59 extending through the casing into the back of the insulating base and having its head arranged beneath the yoke so as to be covered by the steering column when the switch is mounted on the column.

60 I claim:

1. In a switch of the character set forth, a switch base, a switch operating member rotatably and reciprocably mounted on said base and therefore capable of rotary and 65 push button movements on the base, switch

contacts controlled by the operating member in the rotary and push button movements thereof, and means for locking said operating member against rotary movement without affecting the push button movements 70 of said member.

2. In a switch of the character set forth, a switch base, a switch operating member rotatably and reciprocably mounted on said base and therefore capable of rotary and 75 push button movements on the base, switch contacts controlled by the operating member in the rotary and push button movements thereof, and a single lock mechanism for locking the push button operating member 80 against both rotary and push button movements.

3. A switch of the character described, comprising an insulating base provided with 85 passages extending therethrough from the back to the front of the base, contacts having base portions secured at the back of the base and shank portions projecting freely up through the passages and terminating in yielding contact portions exposed at the 90 front of the base, a cap rotatably mounted on the front of the base covering the exposed portions of the contacts and provided with portions engaging said contact portions, terminals on the base portions of the contacts 95 at the back of the base and a casing secured to the back of the insulating base and covering said terminals.

4. A switch of the character described, comprising an insulating base having 100 passages arranged in a substantially circular series and extending through from the back of the base to the front thereof, a series of contacts having base portions secured at the back of the insulating base and yielding 105 contact-making portions extending up through the passages to the front of the base, a cap rotatably mounted on the insulating base covering the contact-making portions of the contacts and provided with 110 portions engaging said contact-making portions and a casing secured to the back of the base and covering the base portions of the contacts.

5. A switch of the character described, 115 comprising an insulating base having passages arranged in a substantially circular series and extending through from the back of the base to the front thereof, a series of contacts having base portions secured at the 120 back of the insulating base and yielding contact-making portions extending up through the passages to the front of the base, a cap rotatably mounted on the insulating base covering the contact-making portions of the contacts and provided with 125 portions engaging said contact-making portions, a casing secured to the back of the base and covering the base, the cap having a series of seats in the underside thereof ar- 130

ranged substantially in the arc of a circle, a locking plunger slidably mounted in the base for engagement in said seats and means for projecting said plunger into any one of 5 said seats for locking the cap in different positions to which it may be rotated.

6. In a switch of the character set forth, a switch base, an operating push button on the base, contacts controlled by said push 10 button, a sliding pin on the base adapted for projection into engagement with the push button, an independently operable switch controlling member on the base and a rotating locking element having connection with 15 the push button locking pin and having a part adapted to be projected into the path of movement of the independently operable switch controlling member.

7. In a switch of the character described, 20 the combination of an insulating base, a cap having a pivot stud rotatably engaged in said insulating base, contacts mounted on the base and covered by said cap, means on the underside of the cap for engagement 25 with said contacts, a terminal on the back of the base, a conducting strip connected with said terminal and electrically connected with the pivot stud of the cap and a relatively stationary contact on the base adapted 30 for electrical connection with said pivot stud.

8. In a switch of the character set forth, a switch base, a switch operating member rotatably mounted on said base, switch contacts controlled thereby, a reciprocatory switch controlling member mounted on the base at an angle to the axis of the rotary operating member, a locking member journaled on the base, a stop carried by said 35 locking member arranged to be positioned in the path of movement of the reciprocatory operating member and a stop member adapted to be projected by the locking member into engagement with the rotary 40 switch operating member.

9. In a switch of the character set forth, a switch base, a rotary push button rotatably and reciprocably mounted on said base, switch contacts controlled thereby in 50 the respective movements thereof, a second independently operable switch controlling member on the base, switch contacts controlled thereby, a rotatable key cylinder mounted on the base, a stop positioned by 55 said key cylinder in the path of movement of the second independently operable switch controlling member and a stop element projected by the rotatable locking element into engagement with the push button aforesaid.

10. In a switch of the character set forth, 60 a switch base, a rotary switch operating member rotatably confined to the base, switch contacts controlled thereby, a reciprocatory switch controlling member mounted on the base substantially at right angles 65

to the axis of the rotary operating member, a locking cylinder journaled on the base substantially at right angles to the planes of the operating members aforesaid, a stop lug on the locking cylinder arranged to be 70 positioned thereby in the path of movement of the reciprocatory operating member, a sliding pin for engagement with the rotary switch controlling member and operating connection between the locking cylinder and 75 said sliding pin.

11. In a switch of the character set forth, a switch base, a locking plug journaled in the base and provided with an eccentrically disposed stop lug and a radially extending 80 cam arm, a locking pin slidably mounted on the base and operated by said cam arm, a switch operating member controlled by said locking pin and a second independently operable switch controlling member controlled by 85 the stop lug aforesaid.

12. In a switch of the character set forth, a switch base, a locking plug journaled in the base and provided with an eccentrically disposed stop lug and a radially extending cam 90 arm, a locking pin slidably mounted on the base and operated by said cam arm, a rotary switch operating member controlled by said locking pin and an independent reciprocatory switch operating member controlled by 95 the stop lug.

13. In a switch of the character set forth, a switch base, a locking plug journaled in the base and provided with an eccentrically disposed stop lug and a radially extending 100 cam arm, a locking pin slidably mounted on the base and operated by said cam arm, a rotary push button rotatably and reciprocably mounted on the base and provided with 105 sockets for the locking pin, a second independently operable switch controlling member mounted on the base and controlled by the stop lug.

14. In a switch of the character set forth, a switch base, a rotary push button rotatably 110 and reciprocably confined to said base and provided with locking shoulders on the under side thereof, switch contacts controlled by said push button in the respective movements thereof, a locking plug journaled in 115 the base substantially at right angles to the axis of the push button and provided with a radially projecting arm substantially parallel to the axis of the push button and having a cam slot therein, a locking pin slidably 120 mounted in the base substantially parallel to the axis of the push button, having a lug engaged in the cam slot and adapted to be projected thereby into engagement with the locking shoulders on the push button, a reciprocatory switch element mounted on the base, at one side of the locking plug and substantially at right angles to the axis of the push button and a stop lug on the locking plug arranged to be positioned thereby in 125 130

the path of movement of the reciprocatory switch element.

15. In a switch of the character set forth, a switch base, a push button journaled on said base and provided with locking sockets in the under side thereof, switch contacts controlled by the rotary push button in the rotary and push button movements thereof, a locking pin extensible up through the top of a 10 base into engagement with the sockets in the under side of the push button and a key plug journaled in the base connected with the locking pin for projecting the same into engagement in the sockets in the push button 15 ton.

16. In a switch of the character set forth, a switch base, a push button journaled on said base and provided with a series of sockets of different depth on the under side thereof, contacts controlled by said push button in the rotary and reciprocatory movements thereof, a locking pin extensible up through the base into engagement with the different ones of the sockets in the under side of the 20 push button and a key engageable member mounted in the base for projecting the locking pin into engagement with such sockets.

17. In a switch of the character set forth, a switch base, a switch operating member 30 journaled on said base and provided with locking sockets in the underside thereof, switch contacts controlled by said rotary switch operating member, a locking pin extensible up through the top of the base into engagement with the sockets in the underside of the rotary switch operating member and a member journaled in the base and connected with said locking pin for projecting the same into engagement with the sockets 35 in the switch operating member.

18. In a switch of the character set forth, a switch base, a push button contact on said base, an independent set of contacts on said base, switch operating means having rotary 45 and reciprocatory movements on the base and carrying contact means for coöperation with the push button contact and with the independent set of contacts aforesaid, and means on said base for locking the rotary 50 switch operating means in a predetermined position.

19. In a switch of the character set forth, a switch base, a locking plug journaled in the base and provided with an eccentrically 55 disposed stop lug, a switch operating member mounted on the base and controlled by said eccentrically disposed stop lug, a second switch operating member mounted on the

base and means also operated by said locking plug for controlling said second switch 60 operating member.

20. A switch of the character set forth comprising a base, an operating member rotatably and reciprocatably mounted on said base, a set of push button contacts brought 65 into engagement by the push button movements of said operating member, contact elements engaged by the rotary movements of the operating member independently of the push button action thereof and means for 70 locking said compound operating member in a predetermined position.

21. A switch of the character set forth comprising a base, an operating member rotatably and reciprocatably mounted on said 75 base, a set of push button contacts brought into engagement by the push button movements of said operating member, contact elements engaged by the rotary movements of the operating member independently of the push button action thereof and means for 80 locking the operating member immovably on the base in a predetermined position.

22. A switch of the character set forth comprising a base, an operating member 85 rotatably and reciprocatably mounted on said base, a set of push button contacts brought into engagement by the push button movements of said operating member, contact elements engaged by the rotary movements of 90 the operating member independently of the push button action thereof, a locking slide mounted on the base for engagement with the push button and key operated means for shifting the locking slide into engagement 95 with the push button.

23. In a switch of the character described, a switch base, a switch operating member rotatably mounted on the top of said switch base, switch contacts controlled by said rotatable member, a reciprocatory switch operating member projecting from the side of the switch base and a lock on the switch base for locking both the rotary switch operating member on the top of the base and the reciprocatory switch operating member at the 100 side of the base.

24. In a switch of the character set forth, a switch base, switch operating mechanism rotatably and reciprocatably mounted on the 110 base, switch contacts controlled by said mechanism in the respective movements thereof and means for locking said mechanism against both reciprocating and rotary movements.

JOHN F. CAVANAGH.
